UNITED STATES PATENT OFFICE

HARRY S. BENJAMIN, OF DETROIT, MICHIGAN

VENDING MACHINE

Application filed May 11, 1928. Serial No. 276,829.

This invention relates to a machine for vending merchandise and more particularly to that class of such machines wherein the operation of the machine is controlled by the insertion of a coin.

An object of the present invention is to prevent the operation of the machine by the insertion of a spurious coin or other device simulating a coin, and to guard against non-
10 delivery of merchandise due to uncompleted operation of the machine and consequent loss to the operator of coins inserted. A further object is to increase the capacity of the machine and insure continued delivery, and
15 further, to provide compact and efficient mechanism together with certain other new and useful features, all as hereinafter more fully set forth.

With the above and other ends in view, the invention consists in the matters hereinafter set forth and more particularly pointed out in the appended claims, reference being had to the accompanying drawings in which

Figure 1 is a transverse vertical section 25 through a machine illustrative of an embodiment of the invention and showing the mechanism in elevation with portions broken away and in section;

Fig. 2 is a detail of the unlatching portion 30 of the mechanism;

Fig. 3 is a cross-sectional detail substantially upon the line 3—3 of Fig. 1;

Fig. 4 is a similar sectional detail upon the line 4—4 of Fig. 1;

Fig. 5 is a longitudinal vertical section 35 through the machine substantially upon the line 5—5 of Fig. 1;

Fig. 6 is a horizontal section substantially upon the line 6—6 of Fig. 5;

Fig. 7 is an enlarged sectional detail substantially upon the line 7—7 of Fig. 1 and showing intermediate portions broken away to shorten the figure;

Fig. 8 is a sectional detail on the line 8—8 45 of Fig. 7;

Fig. 9 is a sectional detail substantially upon the line 9—9 of Fig. 7;

Fig. 10 is an enlarged sectional detail substantially upon the line 10—10 of Fig. 1 with parts broken away and in elevation;

Fig. 11 is a transverse section upon the line 11—11 of Fig. 10;

Fig. 12 is an enlarged sectional detail upon the line 12—12 of Fig. 1;

Fig. 13 is a sectional detail similar to that 55 of Fig. 11 and substantially upon the line 13—13 of Fig. 10;

Fig. 14 is a sectional view showing the reverse side of Fig. 13;

Fig. 15 is a sectional detail similar to Fig. 60 13 with the parts in a different position to illustrate their operation;

Fig. 16 is a detail of a cam and adjacent parts for operating a spurious coin scraper;

Fig. 17 is an enlarged sectional detail substantially upon the line 17—17 of Fig. 1;

Fig. 18 is a perspective detail of coin stop mechanism and adjacent parts of a coin chute;

Fig. 19 is an enlarged detail showing a 70 section substantially upon the line 19—19 of Fig. 1; and

Fig. 20 is a transverse section upon the line 20—20 of Fig. 19.

This machine comprises any suitable form 75 of casing 1 for enclosing the vending mechanism and merchandise to be sold, said merchandise being shown as in the form of small rectangular packages 2 in superposed relation within a series of chutes or magazines 80 3 of any suitable form and construction for retaining these packages in vertical columns and permitting each column to slide freely downward therein as the packages are removed, one at a time from the lower end of each column by means of rotatable feed members or blocks 4, one of said feed members being located directly beneath each column and each formed with two notches or recesses 5 each of a shape and size to receive 85 a single package and located in diametrically opposite sides of the feed block which is of cylindrical form as clearly shown in Fig. 9.

A side wall of each magazine is extended downwardly and curved as at 6 to conform to 90 the curvature of the cylindrical surface of the block, thus forming a guide or shield to hold within the recess in the block, the package removed from the lower end of the column when said block is rotated, said shield 100

ending at the upper end of a chute 7 which leads to a delivery cup opening through the front wall of the casing, so that at each half revolution of each block, a package will be delivered.

In the present construction and arrangement as shown in Figs. 5 and 6, there are five parallel magazines and the feed blocks 4 beneath the first two magazines at one end of the machine, are secured to a sleeve or tube 9 passing through an axial bore in these blocks, and extending through this sleeve is a shaft 10 which shaft also extends through an axial bore in the other three blocks which are secured directly to the shaft by means of set screws, the first two blocks being secured directly to the sleeve 9 by set screws. The first two blocks controlling the delivery from the first two magazines are therefore turned by means of the sleeve 9 and the other blocks for the other magazines are turned by means of the shaft 10.

The two blocks are secured to the tube 9 in such relation that when the recesses 5 in one block are at the top and bottom sides thereof, the recesses of the other block are at the front and rear sides, and therefore at each quarter rotation of the sleeve, a package is discharged.

The other three blocks controlling the delivery from the other three magazines are secured to the shaft 10 at a relative angle of sixty degrees and the shaft is turned one sixth of a revolution with a step by step movement, by means of a ratchet wheel 11 on the projecting end of the shaft as shown in Fig. 8, so that a package will be discharged from some one of the three magazines upon each actuation of the shaft.

The sleeve 9 is rotated through an angle of ninety degrees independently of the shaft 10 by means of a ratchet wheel 12 on the projecting end of the sleeve, thus rotating the blocks secured thereto to discharge a package from either one or the other of the two magazines controlled thereby, at each actuation of said sleeve.

Mounted upon the shaft 10 adjacent the ratchet 11 and free to turn thereon, is an arm 13 and pivoted to the free end of this arm, is a pawl 14 adapted to engage and turn the ratchet 11, and a gravity dog 15 pivoted adjacent the ratchet prevents retrograde turning movement of the ratchet. A like arm, pawl and dog are also provided adjacent the ratchet 12 for turning the same and preventing backward turning movement thereof.

Pivottally attached to the outer or swinging end of each arm 13, is a bar 16 having a laterally extending arm 17 near its upper end provided with a slot 18 to receive a pivot pin 19 for connecting the bar to the end of the arm 13 so that upon downward movement of either bar 16, the arm 13 to which it is connected, will be swung and upon upward movement of the bar, will rotate the

shaft 10 or sleeve 9, depending upon which bar is actuated. This downward movement of one of the bars 16 and swinging movement of the attached arm 13, brings the pawl 14 into engagement with another notch of the ratchet 11 or 12, and upon upward movement of the bar, power will be applied to turn the ratchet and shaft or sleeve to which it is attached, thus rotating the feed blocks attached thereto through either sixty or ninety degrees depending upon which ratchet is turned, and deliver a single package from one or another of the several magazines.

An operating shaft 20 projects through the front of the casing 1 and is provided on its outer end with an operating handle 21, and sleeved upon the inner end portion of this shaft 20 to turn thereon independently of the shaft, is a sleeve 22 (Fig. 10) having keyed thereto, a cam member having two external cams 23 and 24 (Figs. 19 and 20) to engage pairs of pins or studs 25 and 26 on laterally extending lower end portions of the bars 16, said end portions of the bars being formed with vertically elongated openings 27 to receive the shaft and sleeve and permit these bars to move vertically. On each bar there are two studs, one at each side of the slot 27 in the bar, and normally, the bars are held in raised position by the engagement of the cams 23 and 24 beneath the studs at one side of the slots.

Upon rotation of the sleeve 22 and cam member secured thereto, the bars will descend provided they are not held against such movement by latch mechanism hereinafter described, and will descend by gravity to the full extent of movement permitted by the slots 27, and turn the arms 13 to engage the pawls 14 with the next notch of the ratchets 11 and 12, so that upon further turning of the cam member in the same direction which brings the cams 23 and 24 into engagement with the studs at the other side of the slots 27, the bars will be positively raised by said cams and thus, through the engagement of said pawls with said ratchets, rotate the delivery blocks 4 through the necessary angle to discharge the packages.

To control the operation of the operating bars 4 so that they or either one or the other of the same will be held against downward movement and thus prevented from operating the particular delivery mechanism operated thereby, the upper end of each bar is formed with a lateral projection or lug 28 to be engaged by a lateral tooth or projection on a latch bar 29, which latch bars are pivotally supported at their lower ends upon a stud 30 passing through an opening therein and through longitudinal slots in said bars. The bars are thus guided at their upper ends in their up and down movements, by the stud 30, and at their lower ends by the shaft 20 and sleeve 22 engaging the slots 27, with the

latch bars 29 positioned to swing toward and from said bars into and out of engagement with the lugs 28 on said bars and to latch said bars in their raised position when so engaged therewith.

5 To disengage each latch bar 29 and permit each bar 16 to fall, a link 32 is pivotally attached to the upper end of each latch bar, and each link is pivotally attached intermediate its ends to the lower end of a lever 33 pivotally supported at 34 intermediate its ends, the upper end of each lever being connected by a rod or bar 35 to a suitable pawl pivotally supported adjacent the front side of the casting 1 and adjacent slots or openings 36 and 37 therein through which coins may be inserted.

10 The pawl 38 which is adjacent the slot 36 is pivotally supported at 39 intermediate its ends with its lower end pivotally connected to the rod 35, and at its upper end, is formed with a sharp laterally projecting tooth or lug 40 to normally engage beneath a slide 41 guided in its vertical movement upon pins or studs passing through vertical slots 42 in said slide. A spring 43 normally holds this slide in raised position with a laterally bent portion or flange 44 extending across the lower end of the slot 36 and when this slide is 15 forced downward against the action of said spring, by forcing a coin into the slot 36 and into engagement with the flange 44 on the slide, the pawl 38 is rocked on its pivot 39 by reason of the rounded lower end of the slide 20 being in contact with the inclined upper side of the tooth 40, thus exerting a pull upon the rod 35 which will rock the rocker bar or lever 33 and through the connection of its lower end with the latch bar 29, disengage said latch from the bar 16 which is connected 25 through the arm 13 to the sleeve 9 upon which the feed blocks 4 controlling the delivery from the first two magazines, are secured. The insertion of a coin through the slot 36 thus unlatches the bar 16 so that it may descend and bring the pawl 14 into engagement with an advance notch, ready to turn the sleeve and deliver a package from one of the first two magazines when said bar is raised 30 by the turning of the operating shaft 20.

35 The pawl 45 which lies adjacent the slot 37, is pivotally supported at its lower end and to its upper end, the rod 35 is connected. Adjacent said slot 37 is a slide 46 similar to the slide 41 and having a like flange to extend across the lower end of the slot. This slide is guided by slots 42 in the same manner as the slide for the slot 36 and is normally held at the upper end of its movement by a spring 43. 40 The pawl 45 is formed with a hook 47 extending laterally therefrom over the slide 46 to engage over a notched lug 48 on the slide, when said slide is forced downwardly by the insertion of a coin and thus swing said pawl 45 toward the slot as the slide descends, bring-

ing the rounded lower side of its lug 48 into engagement with the rounded or curved upper end of the hook 47. This swinging movement of the pawl 45 thus operates through the rod 35, rocker 33, and link 32 to release the latch 29 holding the bar 16 which is connected to the arm 13 on the shaft 10, thus releasing said bar 16 so that it will drop by gravity and carry the pawl 14 into engagement with the next notch of the ratchet 11 on the shaft 10, so that when said bar is raised by the turning of the cam 24, on the operating shaft 20, a package will be delivered from one of the three magazines controlled by the delivery blocks secured to said shaft 10.

45 The delivery of merchandise from the first two magazines is therefore controlled by the insertion of a coin in the slot 36, and the delivery of merchandise from the other three magazines is controlled by the insertion of a coin in the slot 37.

50 To prevent the insertion of a coin through the slot 37 immediately after the insertion of a coin through the slot 36, the slide 41 is formed with a notch 49 which is engaged by the tooth 40 on the upper end of the pawl 38, thus holding the slide in the position to which it has been moved, and the lower end of this pawl has a projection 50 which is brought into engagement with a notch on the slide 46, thus locking this slide against being moved by a coin and preventing the insertion of a second coin through the slot 37.

55 In a like manner, when the slide 46 is moved downwardly by the insertion of a coin in the slot 37, the pawl 38 is locked against swinging movement by the lug 50 contacting the side of the slide 46, thus preventing the slide 41 from being moved downward to unblock the slot 36. The slide 46 is also held at the lower end of its movement when moved by the insertion of a coin through the slot 37, by the engagement of the hook 47 over the lug 48 on said slide 46.

60 The insertion of a coin through either of the slots 36 or 37 therefore operates to release the latch 29 connected to the pawl opposite the slot through which the coin is inserted and the operated slide is locked at the lower end of its movement, thus holding the latch 29 operated thereby, out of engagement with its bar until such time as the pawl holding the slide is released by an upward movement of the bar 16 which has just been released, such release of the pawl being effected by means of a dog 51 pivotally attached to each bar 16 at a distance below the pivot 30 of the latch 29, said dog being arranged to engage a downward extension of arm 52 on said latch as the bar moves upwardly carrying the dog with it, said dog being so pivoted as to swing freely upward and pass the arm when the bar falls and to be held in a horizontal position in the path of the lower end 65

of said arm when the bar carrying the dog moves upwardly.

The positive or upward movement of each bar 16 effected by the turning of the cams 23 and 24, thus releases the locked slides and permits them to be returned to normal or inoperative position by their springs 48, but as the delivery of merchandise from the magazines is controlled by this same upward movement of the bars 16, this release of the slide is not effected without a corresponding delivery operation of the delivery mechanism.

To prevent the release of the bars 16 by the insertion of a coin when any one of the magazines, the delivery from which is controlled by one of said bars, is empty, a weight 53 is placed in each magazine upon the stack of packages therein, and each weight is provided with a stud or finger 54 projecting laterally from the weight through a vertical slot in the rear side of each magazine.

At the rear of the row of magazines is a pair of bars 55 and 56, the bar 56 being pivoted at one end beyond the three magazines, the delivery from which is controlled by the three feed blocks 4 secured upon the shaft 10, and extends past all of the magazines with its upturned free end 57 (Fig. 1), normally maintained by a light spring 58, in a plane above the horizontal plane of the projecting end of the link 32 which is moved endwise by the insertion of a coin to unlatch the bar 16 which controls the turning of the shaft 10 and operation of the feed blocks in the three magazines.

The bar 55 is pivoted in a like manner at one end and extends across the two magazines having feed blocks secured to the sleeve 9 with its free end 59 normally maintained by a spring 60 in a plane above the horizontal plane of the end of the link 32 which is moved endwise by the insertion of a coin, to unlatch the bar 16 controlling the operation of the feed blocks in said pair of magazines.

The weights assist in feeding the packages by gravity, downwardly in each magazine and when the last package in any one of the magazines has been ejected, the finger 54 on the weight in that particular magazine comes into contact with either the bar 55 or 56 depending upon whether the empty magazine is one of the pair of magazines or one of the series of three, thus depressing said bar against the action of its spring 58 or 60 and bringing the free end of that bar into alignment with the end of the adjacent link 32, preventing the longitudinal movement of said link and through its connection with one of the pawls 38 or 45, preventing the movement of that pawl and consequently the movement of the slide 41 or 46 associated therewith so that the insertion of a coin through the slot 36 or 37 adjacent that particular slide, is prevented, and loss to the customer of the coin is obviated.

As previously described, the operating shaft 20 projects through the forward side of the casing 1 where it is provided with the handle 21 for turning the same, and it is the turning motion of this shaft which, by suitable mechanism hereinafter described, is transmitted to the sleeve 22 on this shaft carrying the cams 23 and 24, to actuate the delivery mechanism and deliver the packages 2, one at a time, into the delivery chute 7.

In order that this operating shaft 20 may be operatively connected to the sleeve 22 to turn the same, only after a good coin has been inserted through one of the slots 36 or 37, mechanism which is coin controlled, is provided for effecting such connection and comprises a circular head 61 mounted on the shaft and connected thereto to turn therewith by means of a ball 62 (Figs. 10 and 11) within a radial bore in the head to engage a series of pockets 63 formed in the shaft, said ball being forced strongly into one of said pockets by means of a coiled spring 64 in the bore between a plug 65 in the outer end of the bore and said ball. This strong frictional or ratchet connection of said head to said shaft is provided to prevent breakage of the operating mechanism should the shaft be turned further in either direction than is necessary to operate said mechanism, the resistance to such further turning offered by the mechanism without breakage, being sufficient to compress the spring 64 and permit the shaft 20 to turn without turning the head 61, but this yieldable connection ordinarily offers sufficient resistance to cause the shaft and head to turn together and operate the delivery mechanism.

The sleeve 22 and shaft 20 may turn, one independently of the other except when connected by means operatively positioned between the head 61 and a similar circular head 67 integral with the sleeve 22 and which heads are in opposed relation but spaced apart.

On the hub of this head 67, which hub projects toward the head 61, is a radially projecting lug 68 (Figs. 5, 10 and 14) adapted to be engaged by a foot 69 on a dog 70 which is pivotally attached by a screw 71 to the side face of the head 61. This dog 70 is controlled in its operation to connect said operating shaft with said sleeve, by means of a lever 72 pivotally supported at 73 intermediate its ends and provided with a laterally projecting pin 74 at its lower end to engage a concentric groove 75 (Fig. 5) in the side face of the head 67 and to be deflected by a swinging movement of said lever, into a peripheral groove or cut-away portion 76 in said head, said lever being also provided adjacent its lower end with a pin 77 extending laterally therefrom (Figs. 5 and 10) and moved by the outward swinging movement of said

lever, into the path of a lug or head 78 on said dog 70.

When the pin 74 follows in its inner path or groove 75, the pin 77 is held out of the path of the head 78 and said dog 70 remains in position with its foot 69 engaged with the lug 68 and the operating shaft and sleeve are caused to turn in unison, through a sufficient degree of rotation to effect the delivery of merchandise or until the said pin 74 reaches the end of the slot 75, thus preventing further rotation of the sleeve in that direction, and just prior to said sleeve reaching such limit of its rotation, a tail projection 79 on the dog 70 comes into contact with the pin 77 on the lever 72, and said dog is thrown out of engagement with the lug 68, thus disconnecting the operating shaft 20 from the sleeve 22 and permitting said sleeve to be at once rotated in a reverse direction by a coiled spring 80 made fast at one end within a peripheral groove in the head 67 and suitably anchored at its opposite end after passing partially around the head, said spring being arranged to be put under tension when the head and sleeve are turned by the engagement of the dog 70 with the lug 68 and the turning of the operating shaft by means of its handle 21.

In a like manner, the operating shaft is turned to normal position after its release by the operator, by means of a coiled spring 81 secured at one end within a peripheral groove in the head 61, passed partially around said head and anchored to a suitable support at its opposite end.

A spring 82 (Fig. 5 and 17) is connected to the lower end portion of the lever or rocker-arm 72 and exerts a force normally tending to swing said lever outwardly of said head 67 and thus cause the stud 74 to leave the groove 75 and enter the peripheral groove 76 of said head when said head is turned from its normal position (Fig. 5) and when the upper end of said arm 72 is free to swing. If, however, said upper end of said arm is prevented from swinging by means hereinafter described, the stud 74 will follow the inner groove 75 of the head and the pin 77 will be held out of the path of the head 78 on the dog 70 and said dog will function to transmit motion from the head 61 on the operating shaft 20 to the head 67 on the sleeve 22 until the dog has been carried around far enough by the turning of the head 61 to bring the tail 79 of the dog into engagement with said pin 77, whereupon the heads will be disconnected and the sleeve and head 67 will be returned to normal position by the spring 80. The throw or degree of turning movement of the head 67 in each direction, is limited by the length of the groove 75 and when the rocker 72 is swung so that said stud 74 passes into the groove 76, the degree of turning movement of the head is limited by the length

of this groove which is considerably shorter than the groove 75, thus preventing the head and sleeve from being turned far enough to bring the cams 23 and 24 (Fig. 19) into position to raise the bars 16, and thus operate the merchandise delivery mechanism.

Therefore, the swinging of the rocker 72 governs the operation of this delivery mechanism, and the swinging of said rocker is controlled by the insertion in the machine of a coin, as will be hereinafter described, the insertion of a good coin operating to prevent such swinging movement, and failure to insert a coin or the insertion of a slug, permitting of such swinging movement.

Should the operator after inserting a good coin, grasp and turn the handle 21 through but a portion of the movement required to complete the operation and deliver a package from one of the magazines, and should he then release the handle, he would receive nothing for his coin provided the parts were permitted to be returned to normal position by the springs 80 and 81 as described, and to prevent such retrograde movement after the sleeve 22 has been turned to a position where the operation of delivering a package has been started, that is, after the upstroke of the operating bars 16 has begun, a portion of the periphery of the head 61 is formed with a series of notches or ratchet teeth 83 to be engaged by the tail portion 84 of a dog 85 pivoted at 86 intermediate its ends upon a suitable support adjacent the periphery of the head 61, said tail being also adapted to engage a tooth or projection 87 on said head to limit the retrograde movement of said head and shaft when the handle 21 is released and hold said head in the normal position shown in Figs. 13 and 14. The end 88 of the dog 85 opposite the end 84, is adapted to engage a tooth or projection 89 on the head 61 when said head has reached the limit of its forward turning movement or when said head has reached such a position that the dog 70 is just brought into engagement with the pin 77 to disengage said dog from the lug 68 and disconnect the head 61 from the head 67 at the end of the merchandise delivery operation.

In order to insure the engagement of the tail 84 of the dog 85 with the teeth 83 when the head 61 is rotated by the handle 21 in the direction of the arrow in Figs. 13 and 14, in the normal operation of the machine when a good coin has been inserted, a latch member or dog 90 is pivotally supported intermediate its ends adjacent the pivot for the dog 85 and has a laterally extending portion 91 at its upper end to engage over a laterally extending lug 92 on the dog, said latch and dog being urged toward each other by a coiled spring 93 connecting upper end portions of said latch and dog, and thus the dog is latched down by the latch with its tail 84 in position

to engage the notches 83 after a certain degree of turning movement of the head, and prevent backward turning of the head by the action of the spring 81.

On the head 61 adjacent the stop or lug 87 thereon, is a laterally projecting pin 94 adapted to engage the downwardly projecting end 95 of the latch 90 just as the end 84 of the dog engages the stop when the handle 21 is released and the head is turned backward to normal or inoperative position by the spring 81, and thus the latch is swung on its pivot and caused to engage over the lug 92 on the dog 85. When the end 88 of the dog 85 engages the projection 89 on the head 61 at the end of the forward rotative movement of the head, at which point the head is released by the tail 79 of the dog 70 coming into contact with the pin 77 at the end of the delivery operation, said dog 85 is turned on its pivot by such engagement with said projection 89, from beneath the latch and the lug 92 is engaged within a notch 96 in the lateral end portion of the latch to hold said dog 85 tilted 25 with its end 84 out of the path of the teeth 83 during the backward turning of the head 61 to normal position.

To control the swinging movement of the upper end of the rocker arm 72 so that when 30 a good coin is inserted in the machine, said arm will be prevented from swinging and will be permitted to swing when no coin or a slug is inserted, and thus through causing the stud or roller 74 to travel in either the groove 75 or the groove 76, control the operation of the machine, as previously described, the following described mechanism is provided:—

Leading from the coin slots 36 and 37 in the front of the casing 1, is a coin chute 97, a 40 rearwardly extending portion of which chute is formed in one wall thereof with a lateral opening 98 so arranged that should a coin of less diameter than that of a coin adapted to operate the machine, be inserted, said small 45 coin will fall out laterally of the chute through this opening and the machine will fail to operate to deliver a package of merchandise, due to the lack of a coin passing down the entire length of the chute. Should 50 a metal slug be inserted, such slug will be attracted to a magnet 99 supported adjacent the chute with its ends projecting therein and the slug will be held by this magnet until removed by a sweep 100 positioned within the 55 chute and normally supported upon a pivoted arm 101 above the horizontal plane of the slug held by the magnet, as shown in Fig. 1. This arm 101 is actuated by a rod 102 pivotally connected thereto at its upper end to swing 60 the arm downwardly and cause the sweep 100 to come into engagement with and sweep the slug from the magnet, permitting it to pass on down the chute after being so delayed. The rod 102 is pulled downwardly to swing 65 the arm 101, by means of a cam 103 (Fig. 16)

secured to the operating shaft 20 and engaging a pin 104 on a slide 105 to which slide the lower end of the rod is pivotally attached. The slide is guided in its vertical movement by providing longitudinal slots 106 therein through one of which the shaft 20 extends and through the other of which a fixed supporting rod 107 extends, said rod 102 and slide 105 being moved in an up or opposite direction by a spring 108.

Therefore, whenever the operating shaft 20 is turned by its handle 21, after the insertion of a slug, the sweep 100 is operated to remove the slug caught by the magnet 99 and permit it to drop down the chute, deflecting means being provided to deflect said slug from said chute before it reaches the lower end portion of the chute, said deflecting mechanism comprising a deflecting arm 109 (Fig. 1) pivotally supported at its upper end adjacent the edge of the chute and provided with a curved foot or deflector 110 on its lower end adapted to be projected through an opening in the chute when said arm is swung on its pivot by the descent of the rod 102 which is provided with a pin 111 to engage within an elongated notch in the side of said arm and positively swing said arm toward the chute when the rod descends and away from said chute to withdraw its deflecting foot from the chute when said rod is raised. When the deflector foot is in the path of a slug descending in the chute, said slug will be deflected thereby into a branch chute 112 which leads into the delivery cup 8 (Fig. 5) and thus such a slug will be returned to the operator without functioning to prevent the swinging movement of the rocker arm 72 and to cause the merchandise delivery mechanism to function.

Before a slug or coin passing down the chute 97 reaches the deflector 110, it comes into contact with a pivotal finger 113 (Fig. 17) projecting into the chute across the path of the slug or coin so that said finger will be turned on its pivot against the action of a very light spring 114 by the weight of said slug or coin falling thereon. A connecting rod 115 is pivotally connected to said finger laterally of the finger pivot and at its lower end is pivotally attached to a latch bar 116 at one end of said bar, said bar being pivotally supported at its opposite end to swing alongside the chute 97 adjacent an opening in one side of the chute through which opening the laterally bent end 117 of a plate 118 is adapted to be projected across the chute by the turning of said plate upon its pivotal support 119.

A spring 120 normally exerts a force to turn said stop plate 118 on its pivot and project its laterally bent end 117 through the opening in the chute, across the path of a coin falling down said chute (Figs. 17—18), and to hold said plate against the action of said spring 120 with its stop portion or bent end 130

117 retracted from the chute, said latch bar semi-circular member 129 which is secured 70 to the head 61 and passes over the edge of the head 67, into engagement with a cam arm 130 extending downwardly from and rigidly connected to the lower end of the plate 118. Therefore, rotation of the head 61 by means of the handle 21 brings the semi-circular flange 128 into engagement with the cam arm 130, swinging said arm and also the plate 118 against the action of the spring 120 and withdrawing the stop 117 from the chute, thus permitting the coin supported thereby to pass on down the chute, completing the full 75 operation of the machine.

118 If the piece inserted be a slug, it will be held by the magnet sufficiently long to permit the deflector 110 to be projected across the chute in time to deflect the slug and whether it be a slug or a coin, the same will strike the finger 113 and release the stop 117 to time to block the passage of the coin or slug from the chute and, therefore, should a slug having a central hole therein, such as a washer, be inserted and not be caught by the magnet, said 80 slug washer will be blocked and held by the stop 117 with the hole in the washer opposite the opening 122 in the chute.

119 To control the swinging movement of the rocker arm 72 for the purpose previously set forth, a plunger 123 is guided in a horizontal plane for longitudinal movement, within a suitable bearing support 124, and this plunger has a reduced and sharpened end projection 125 adapted to be projected through 85 the opening 122 in the coin chute when said plunger is moved longitudinally. The opposite end of this plunger is pivotally connected to the upper end of the rocker arm 72 by a transverse pin 126 passing through a longitudinal slot in the arm, and said plunger 90 comprises two hollow telescopic parts with a coiled spring 127 therein interposed between said parts to provide a slight longitudinal yielding action.

120 When a good coin is inserted, the stop plate 118 is released by the impact of the coin against the finger 113 and the stop 117 is projected across the chute before the coin reaches that point. Said coin is therefore 105 stopped in its movement down the chute and held in position opposite the opening 122 so that when the head 67 is rotated and the spring 82 tends to swing the rocker arm 72, such swinging movement will be prevented 110 by the end of the plunger 123 coming into contact with the coin which is held opposite the opening through which the end of the plunger is adapted to be projected, and further turning of the head will bring the stud 115 74 into the inner groove, permitting continued rotation of the head and through such rotation, the operation of the merchandise delivery mechanism. This continued rotation of the head 67 and corresponding rotation 125 of the head 61, brings a flange 128 on a

80 Should this coin or device which is stopped opposite the opening 122 have a central hole in it, such a coin or device will allow the sharpened end 125 of the plunger 123 to pass therethrough, and thus by the longitudinal movement of said plunger, permit the rocker arm 72 to swing, bringing its stud 74 into the outer path 76 of the head 67 and effecting a disconnection between said head 67 and the head 61 before the delivery mechanism has been actuated to deliver a package, as previously described.

85 With this arrangement, the insertion of a coin in the machine first serves to unlock the merchandise delivery mechanism so that it may be operated through the medium of the operating handle, otherwise the entire mechanism is inoperative, and the turning of the handle accomplishes nothing. This coin if it be a good coin then serves to control the operation of the mechanism for transmitting motion from said handle to the delivery mechanism, but if it be a slug, or the like, this substitute for a coin will either be ejected before it reaches and operates to control the 90 operation of the mechanism for transmitting motion to the delivery mechanism, or will fail to so function due to its being in the form of a common washer. Loss to the operator of coins inserted by mistake and breakage of the mechanism is also obviated by the construction. Control of the delivery of merchandise is effected through the control of the single rocker arm 72 by means of the coin or substitute therefor, thus simplifying the construction and providing a compact mechanism which may be housed within a comparatively small space.

95 Obviously changes may be made in the construction and arrangement of parts, within the scope of the appended claims, without departing from the spirit of the invention, and I do not, therefore, limit myself to the particular construction shown.

100 What I claim is:—

105 1. In a vending machine, the combination of a rotary member, a manually operated operating member rotatable independently of said rotary member, means for connecting and disconnecting said members, a lever for con- 110

115 115 120 125 130

- trolling the operation of said connecting means and provided with means for engaging one of said members, said member being formed with two paths of travel for said 5 means, and means whereby the path of travel taken by said means is determined by the insertion of a coin. 70
2. In a vending machine, the combination of a rotary head, a rotary manually operated 10 member having a head, said heads being an opposed relation and independently rotatable and one of said heads being formed with connected paths, a member for operatively connecting said heads, a lever for operating 15 said connecting member, means on said lever to travel along one of said paths, and coin controlled means for determining the position of said lever to cause said lever to follow one or the other of said paths, said lever 20 being adapted to operate said connecting member to dis-connect said heads when said lever is caused to follow one of said paths. 75
3. In a vending machine, the combination of a rotary member, a manually operated operating member in opposed relation to said 25 rotary member, a connecting member for transmitting motion from said operating member to said rotary member, a lever pivoted intermediate its ends with one end positioned to operate said connecting member, a plunger connected to the opposite end of said lever, and means for positioning a coin in the 30 path of said plunger to restrict the movement thereof and control the operation of the connecting member. 80
4. In a vending machine, the combination of a rotary head, a manually rotated operating member having a head in opposed relation to said rotary head, one of said heads being 35 formed to provide connected travel paths, a lever between said heads having a stud to engage in one or the other of said paths, a connecting member for transmitting motion from one to the other of said heads, means on 40 said lever to engage and operate said connecting member when said stud is traveling in one of said paths, and means controlled in its operation by the insertion of a coin, for controlling the operation of said lever and determining which path of travel said stud 45 thereon shall follow. 85
5. In a vending machine as characterized in claim 4 and wherein springs are arranged to be put under tension when said heads are 50 rotated in one direction by said operating member and serve to rotate said heads in an opposite direction when said heads are disconnected and said operating member is released. 90
6. In a vending machine as characterized in claim 4 and including a spring for rotating said operating member in a direction reverse to that in which it is turned to operate said rotary head, and means for preventing such 55 reverse turning of said operating member by 95
- said spring, operable throughout a portion of said rotative movement. 100
7. In a vending machine, the combination of a rotary member, a manually operated operating member in opposed relation to said rotary member, a connecting member for transmitting motion from said operating member to said rotary member, a lever for controlling said connecting member, a coin stop member positioned to support a coin with said coin positioned to limit movement of said lever, and a member rotatable with said operating member for operating said coin stop member. 105
8. In a vending machine as characterized in claim 7 and wherein a longitudinally reciprocable member is connected to said lever and positioned to engage a coin and limit the movement of said lever and said coin stop member is moved into and out of coin supporting position by a cam lever on said member, said cam lever being engaged and operated by said member rotatable with said operating member. 110
9. In a vending machine, the combination of a rotary member, a manually operated rotatable operating member in opposed relation to said rotary member, a connecting member for transmitting motion from said operating member to said rotary member, a lever for controlling said connecting member, a longitudinally reciprocable plunger connected to said lever, a coin stop member pivotally supported for projection into the path of a coin to support said coin in the path of movement of said plunger, latch mechanism for holding said stop member, a spring for moving said stop member when released by said latch, a trip member adapted to be engaged by a coin to trip the same and release said latch, and a cam member for moving said stop member against the action of said spring, said cam member being operated by rotation of said manually rotated operating member. 115
- In testimony whereof I affix my signature. 120
